US0D1062413S

(12) **United States Design Patent** (10) **Patent No.:** **US D1,062,413 S**
(45) **Date of Patent:** **** Feb. 18, 2025**

(54) **POWER CUTTER ARM**

(71) Applicant: **HUSQVARNA AB**, Huskvarna (SE)

(72) Inventors: **Ricardo Sa Freire**, Johanneshov (SE);
Joakim C. Hanell, Huskvarna (SE)

(73) Assignee: **HUSQVARNA AB**, Huskvarna (SE)

(**) Term: **15 Years**

(21) Appl. No.: **29/887,398**

(22) Filed: **Mar. 21, 2023**

(30) **Foreign Application Priority Data**

Sep. 22, 2022 (EM) 009182520-0003

(51) **LOC (15) Cl.** **08-03**

(52) **U.S. Cl.** **D8/66**
USPC .....

(57) **CLAIM**

The ornamental design for a power cutter arm as shown and described.

DESCRIPTION

FIG. 1 is a perspective view of a power cutter arm embodying our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate portions of the power cutter arm that form no part of the claimed design.

1 Claim, 7 Drawing Sheets
